UNITED STATES PATENT OFFICE.

AXEL ENGNELL, OF CHICAGO, ILLINOIS.

SOUND BOX.

Application filed March 20, 1919, Serial No. 283,784. Renewed July 9, 1923.

To all whom it may concern:

Be it known that I, AXEL ENGNELL, a citizen of the United States, residing at Chicago, in the county of Cook and State of Illinois, have invented certain new and useful Improvements in Sound Boxes, of which the following is a specification.

My invention relates to sound boxes and particularly to novel means of mounting 10 the stylus bar on the sound box.

Among the objections to the present style of mounting a stylus on a sound box is that when the stylus bar is moved by the undulations in the record groove, 15 the movement of the diaphragm is affected to a certain extent when the movement of the needle is considerable. In sound boxes employing springs for mounting the stylus arm, the springs tend to 20 dampen the vibrations of the diaphragm and conversely it is necessary that the diaphragm exert some influence to overcome spring resistance when the vibrations of the needle are out of the ordinary.

One of the objects of my invention is to 25 provide a stylus bar mounting for sound boxes which will eliminate the undesirable relationship between the diaphragm and the stylus arm mounting to remove any dampening effect on the diaphragm.

Another object is to provide a stylus arm 30 mounting for sound boxes which will permit proper reproduction of sounds without dampening or otherwise retarding the effectiveness of the diaphragm.

A further object is to improve stylus arm 35 mountings for sound boxes for successful commercial use.

Generally speaking I accomplish the objects of my invention by providing a knife edge engagement between the stylus arm 40 and the sound box and mounting the tension spring wholly on the stylus arm so that the same may be movable with the 45 arm as the diaphragm is vibrated.

These and other objects of my invention 50 will be apparent from an inspection of the drawings wherein—

Figure 1 is a front elevational view of 55 a sound box provided with the preferred embodiment of my invention.

Figure 2 is a back elevational view of the 60 sound box in Figure 1, a portion of the parts being shown in section.

Figure 3 is a vertical sectional view of 65 my invention, and

Figure 4 is an enlarged sectional view 60 taken in the plane of line 4—4 of Figure 1 showing the preferred means of mounting the stylus arm on the sound box.

In the form which I have chosen to illustrate my invention, I provide a sound box 65 having a substantially solid back member 5 which has a centrally disposed opening 6 therethrough for transmittal of the sound to the tone arm. The diaphragm 7 is mounted between the usual resilient washers 8 and held in place by a ring 9 secured to the back plate 5 by screws 10 or other suitable fastening means. Preferably, the 70 screws are inserted through the back of the sound box. The lower portion of the back member 5 is provided with an extension 11 the purpose of which will be explained later.

Referring more particularly to Figure 3, 75 it will be observed that the stylus arm is an integral member fastened at its upper end by means of an inside screw 12 to the center of the diaphragm 7 and provided at 80 its lower end with a needle receiving aperture 13 having the usual set screw 14 for positioning the needle 15 in operative position. For supporting the stylus arm on the sound box, I employ a pair of knife edged 85 members 16 and 17 (Fig. 4) adapted to engage recesses 18 in the front face of the downwardly extending projection 11 of the sound box back. Preferably the members 16 and 17 are spaced apart as shown in the 90 drawings. In the back side of the projection 11 I form a pointed recess 19 into which projects a pointed pin 20. The pin member 20 is riveted or otherwise secured to a flat spring 21 mounted as seen in Fig. 95 3 at some distance from the back of the projection 11. Screws 22 and 23 retain the spring 21 under tension which screws are in threaded engagement with the lower portion of the stylus arm, the screw 22 engaging the stylus arm below the bottom of the 100 projection 11, and the screw 23 above the lower end thereof, projection 11 being formed with a suitably disposed aperture 105 24 through which the screw 23 extends, and in which the screw is permitted freedom of bodily movement. The engaging edges of the knife members 16 and 17 and the point of the pin 20 I arrange to engage the extension member 11 in the same horizontal 110 plane and in the same vertical plane so that any rocking movement of the stylus

arm on the projection 11 will prevent any friction as the arm is moved and by reason of the line and point contacts, resistance and friction is reduced to a minimum. 6 Furthermore, such an arrangement permits rocking the stylus arm on the support in such manner that no tension is placed upon the spring when so rocked. Consequently, the spring does not tend to oppose movement of the diaphragm as the same is vibrated when the needle is in engagement with the sound grooves of the record. The degree of freedom of movement of the stylus arm and consequently the vibration of 10 the diaphragm may be regulated within certain limits by tensioning or loosening the spring 21 which will vary the degree of gripping engagement between the knife edges 16 and 17 and the point 20 with the 15 sockets or recesses with which these are in engagement. Such an arrangement permits free oscillation of the stylus arm with minimum resistance thereto resulting in perfect reproduction of sounds that are but 20 lightly recorded on the record and furthermore, reducing the wear of the record by reason of the fact that neither the spring nor the diaphragm tend to oppose movement of the needle as the same is in the 25 record groove. Furthermore, such mount-

ing serves to keep the diaphragm in a neutral plane and to prevent creation of overtones as a result. The mounting of the spring on a seat such as disclosed in my invention, permits the stylus arm to oscillate 30 freely about the fulcrum point as the fulcrum point of the spring is in line with the fulcrum point of the stylus bar, hence no opposition to the movement of the stylus bar is created. 40

There may be various modifications of the invention and it is my intention to cover all modifications falling within the spirit and scope of the following claim.

I claim:—

A sound box construction including a support, a stylus bar, means for mounting said stylus bar on said support, said means including bearing means carried by said bar and engaging said support, bearing means engaging the opposite side of said support, said plurality of bearing means defining the axis of oscillation of said stylus bar, and a plurality of members mounted on said bar on opposite sides of said axis of oscillation for maintaining said bearing means in engagement with said support. 50

Signed at Chicago, Illinois, this 18th day of March, 1919.

AXEL ENGNELL.
